GAME BOARD, OR SIMILAR ARTICLE

Raymond H. Lecomte, 501 N. Main St., Brockton, Mass.

Filed Apr. 30, 1964, Ser. No. 79,745

Term of patent 3½ years

(Cl. D34—5)

Fig. 1.

Fig. 2.

FIG. 1 is a top plan view of a game board showing my new design, and

FIG. 2 is a side elevational view thereof.

All depressions and the ornamentation are flush on the board.

The dominant features of my design reside in the portions shown in full lines.

I claim:

The ornamental design for a game board or similar article, substantially as shown and described.
